UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

LINE-SPACING MECHANISM FOR ADDING OR TYPE-WRITING MACHINES.

1,208,375.

Specification of Letters Patent. Patented Dec. 12, 1916.

Application filed July 21, 1913. Serial No. 780,266.

To all whom it may concern:

Be it known that I, FRANK C. RINSCHE, a citizen of the United States, residing at Detroit, in the county of Wayne and State of Michigan, have invented a certain new and useful Line-Spacing Mechanism for Adding or Type-Writing Machines, of which the following is a specification.

The present invention relates to spacing mechanism adapted for use in the paper carriages of adding or typewriting machines, and has for its object the provision of means for rapidly turning the roller platen a predetermined distance, varying according to the desired or required adjustment and capable of a maximum adjustment much greater than the usual automatic line spacing of the machine; and, after the desired imprints have been made, for then rapidly discharging the printed sheet by a succeeding operation or repeated operations.

The invention is particularly useful in making out statements, invoices, or bills upon printed forms which provide for the entry of amounts or memoranda at a fixed line some distance below the top of the sheet.

With the above object in view the invention consists in certain novel features of construction and arrangement, and new combinations of parts, the elements of which are more particularly recited and pointed out in the appended claims; and in the accompanying drawings the invention is illustrated in a preferred form of embodiment hereafter described in detail.

The invention as herein described is shown applied to a carriage of familiar type in use upon the well-known Burroughs adding machine, of the general construction shown in Patent No. 924,118, issued June 8, 1909, upon joint application of Jesse G. Vincent and Russell E. Benner.

Of the accompanying drawings Figure 1 shows a right side elevation of the paper carriage of a Burroughs adding machine, the term right side being applied to the side at the right hand of an operator of the machine; Fig. 2 is a vertical section on the line 2—2 of Fig. 1; Fig. 3 is a detail showing a spring connection for returning the operating lever and handle, together with the gear turned by the handle; Fig. 4 is an enlarged left side elevation of the carriage, the moving parts being shown in normal po-

sition; Fig. 5 is a similar view with such parts in the position assumed at the end of an operating stroke; Fig. 6 is a fragmentary right side view broken away to uncover the parts shown in dotted lines in Figs. 4 and 5; Fig. 7 is a plan view on the line 7—7 of Fig. 4; Fig. 8 is a front elevation of the right hand end of the paper carriage, detached from the main frame of the adding machine; Fig. 9 is a section on the line 9—9 of Fig. 8; Fig. 10 is a detail showing in perspective a ratchet pawl connection between the operating lever or handle and circular driving gear; and Fig. 11 is a perspective of a locking pawl setting a movable stop or stud for determining the length of stroke of the operating lever.

The same letters of reference indicate the same parts throughout the drawings.

The paper carriage to which in the present instance my invention is applied is of the particular kind used upon Burroughs adding machines and adapted for the making out of statements and other tabulated work, the frame of such carriage, designated by the reference numeral 2, being mounted to travel to and fro laterally upon a track 3 which is secured to the back panel 4 of the adding machine. Carried in the side plates 15 of a cradle mounted upon the carriage is the roller platen 6, which is equipped with the usual finger-wheel, or twirler and a line detent star wheel 7^c, engaged by a yielding pawl 7^b, the wheel being of the type that is releasable from the platen shaft by a clutch 9 to permit independent turning of the platen. The carriage is equipped with the usual or regular line spacing mechanism, which need not be fully described, but in brief comprises the ratchet wheel 81 upon the roller platen, (see Fig. 8); the arm 82 loosely journaled on the platen shaft; the pawl 80 adapted to engage and turn said ratchet wheel 81; the link 83, said pawl and link being both pivoted to said arm; and the slotted plate 84, with which the link may be engaged in different positions to cause spacing of different numbers of line spaces. This slotted plate is secured to a shaft 12, and in the regular operations of the machine, the plate is rocked by the cross members of an oscillating bail mounted on the frame of the machine and operated through connections which need not be here described to effect the usual line spacing.

To facilitate accurate and even feeding of separate sheets of paper, such as statement blanks, bills, etc., a high and steep paper support or back 10 is employed, this back being secured by brackets 10^a to a cross-rod of the cradle of the carriage in such position that a sheet will drop by gravity directly into the crevice between a pressure roller 13 and the platen. (See Fig. 9). Upon the front face of the paper support are a pair of paper guides 10^b with forwardly projecting flanges, which guides are held on the support by means of friction clips, confined by studs 10^c projecting through horizontal slots in the support, thus providing for lateral adjustment of the guides. With the parts of the paper support having the arrangement described, the sheets will drop naturally into correct position, and the preliminary adjustments usually required to square the paper into proper feeding position is avoided.

The parts thus far mentioned are no part of the present invention, which relates to a mechanism for turning the platen roller which will now be described.

Upon an irregular, upwardly and rearwardly extending portion 15^a of the right side plate 15 of the cradle which carries the roller platen (see Fig. 6), is fixed a stud 16, a short distance above and to the rear of the platen, (Figs. 2 and 6). A large gear wheel 17 having a hub 17^a is journaled on the stud 16, the outwardly-extending portion of the hub 17^a in turn forming a bearing for an operating lever 18 lying adjacent the gear wheel and extending upwardly and terminating in a handle 18^a. A pinion 19 in mesh with the gear wheel 17 is fixed to the platen shaft 8, and through the medium of the gear wheel is turned by the operating lever at a multiplied velocity. The operating lever has a pawl and ratchet connection with the gear 17, a ratchet pawl 21 pivoted on such lever being pressed by a spring 20 into the teeth of the gear 17, and a coil spring 21^a surrounding the hub 17^a of the gear serving to return the lever to its normal rearward position, in which the lug 21^c contacts the stud 21^d on the arm 24, hereinafter described, to disengage the pawl. One end of the spring 21^a is fastened to a stud on the lever and the other end fastened to a stud carried by a shield or cover plate 22 rigidly secured upon the stud 16, (see Figs. 2 and 3). To limit the forward stroke of the operating lever there is provided a fixed stud 22' in the front of the side plate extension 15^a for the flattened end 20^b of the ratchet pawl to strike against, (see Fig. 5), and the length of stroke is varied by an adjustable stud 23 which limits the rearward movement of the lever to its rearward or normal position, (Figs. 1 and 4). This adjustable stud is carried in an arm 24 pivoted on the stud

16 and lying between the hub of the gear wheel 17 and the side plate extension 15^a, said arm being slotted at 23^a to receive a limit stud 23^b fixed in the side plate extension 15^a and serving to limit the swinging of the arm beyond a certain forward and rearward setting. The length of stroke which the operating lever may take is determined by the position of the movable or adjustable stud 23 with respect to the fixed stud 22', and the arm 24 carrying the stud 23 is locked at any desired position within the range of adjustment of the parts by means of a pawl 25 pivoted at 25^a to the arm 24, the forward end of this pawl being equipped with a pair of teeth 25^b adapted to interlock with the teeth of a segmental rack 15^c formed on the upper edge of the side plate extension 15^a to hold the arm in locked position. The pawl is held in engagement with the teeth of the segment by a spring 25^c connecting a rearwardly extending portion 25^d of the pawl with a stud fixed in the arm 24, a knob 25^e on the end of this portion of the pawl serving to release the pawl to permit the arm and stud to be shifted to any desired position of adjustment, (Figs. 4, 6 and 11). Since the normal rearward position of the lever while at rest is determined by the position of the movable stud or stop 23 on the arm 24, the adjustment of the pawl 25 on the rack 15^c serves to adjust the rearward position of the operating lever and thus governs the length of stroke which it is permitted.

To facilitate the proper adjustment or setting of the operating lever for whatever distance of feed may be desired, an index scale is provided, so arranged that when the pawl 25 and consequently the lever is set to any position thereon the stroke of the lever will feed the paper the indicated number of inches, or of subdivisions indicating line spaces. This scale is placed on the segmental upper flange of the shield 22 (see Figs. 7 and 8) and comprises graduations corresponding to the number of inches which the paper may be fed under the design and proportions of the parts of the device, in the present instance from 1 to 7, with intermediate graduations corresponding to line spaces or multiples thereof—in the present case the numbered marks, indicating inches, being subdivided into thirds, indicating each a feeding movement equal to a double line space. Adjustment of the lever to the indication "1" will bring about the revolution of the platen to feed the paper one inch and place it in position to receive imprints one inch from the preceding line; the next intermediate graduation will give a longer stroke and bring the printing point a double line space farther below, and so on, the printing line being brought one double line space farther from the position of the preceding

line of the sheet for each additional step toward the rear to which the lever is set.

In connection with the above described scale, another scale is provided which may be consulted to determine what should be the setting of the index scale to bring the paper to a given printing line on the sheet. This scale is formed on the inner face of one of the laterally adjustable paper guides 10^b which are a part of the ordinary carriage and which are held on the paper support 10 by means of friction clips 10^c (see Figs. 8 and 9). This scale is likewise marked to indicate inches of feed of the paper with intermediate divisions corresponding to those of the index scale on the shield 22, so that when a sheet is laid against the guides with its face exposed and its bottom edge in the crevice marked 12 in Fig. 9, the indication on the scale opposite the line on the sheet where the imprints are to be made may be noted. The paper being then taken up and reversed, and the operating lever being set by means of the pawl 25 to the indication noted, the operation of the handle will feed the paper a proper distance to bring the desired line to the printing point. However, since a considerable preliminary feeding movement is required to bring the top of the sheet opposite the printing point of the machine, it is obvious that it is impracticable to include in this scale the full range of graduations provided for on the index scale, and in the present instance (see Fig. 9) the minimum indication is for a feeding movement of three inches, and the maximum indication seven inches.

In the ordinary operation of the machine the star wheel 7^c of the line detent is engaged by a roller 7^a mounted in a spring-pressed yielding pawl 7^b pivoted upon the frame of the carriage. For the purpose of avoiding the noise incident to the clicking of this roller over the teeth of the star wheel which would otherwise occur with the mechanism hereinbefore described when the platen is rapidly turned by the operating lever 18, provision is made for disengaging the roller 7^a and at the same time substituting for the resistance offered thereby a continuous frictional resistance. To this end the star wheel is provided with a concentric flange, and a short oscillating lever 7^d, pivoted near its center on the yielding pawl 7^b, carries at its upper end a pivoted shoe 27 which normally, when the lower end of the lever is in rearward position, is out of contact with the flange, but which, by the rocking of the lower end of the lever forwardly, may be brought to bear on the periphery of the flange, the flange serving as a fulcrum for forcing the yielding pawl 7^b and roller 7^a down against the stress of the spring. The lever 7^d having been rocked past its center and its lower end stopped by the hub of

the pawl, the spring serves to hold the shoe against the flange 7^c with such pressure as to prevent too rapid rotation of the platen and absorb the shock of sudden stopping, and also to prevent over rotation of the platen which might occur under rapid operation of the operating lever by reason of back lash in the gearing.

While the invention has been described as applied to the well-known Burroughs adding machine it is obvious that it may be applied to adding machines of other types, and also to the carriages of typewriting machines, and the embodiment of the invention described is susceptible of various modifications without departure from the scope and essential principles of the invention.

I claim:

1. A line spacing mechanism for adding machines and the like comprising a platen, 85 a pinion rotatable therewith, a gear wheel meshing with said pinion, a rearwardly spring-pressed operating handle pivoted concentrically with said gear wheel, a pawl carried by said handle and forming a 90 ratchet connection between said handle and gear wheel, a forward fixed stop, and a rearward adjustable stop, said handle normally engaging said last mentioned stop and both said stops being arranged adjacent the path 95 of the handle and cooperating therewith to limit its stroke and the rotation of the platen.

2. In a paper holding carriage for adding machines and the like, a platen journaled 100 in the carriage frame, a pinion rotatable therewith, a gear wheel meshing with said pinion, a rearwardly spring-pressed operating handle journaled concentrically with said gear wheel, a pawl carried by said 105 handle and forming a ratchet connection between said handle and gear wheel, a fixed stop arranged in the path of the handle to limit the throw thereof in a forward direction, a segmental rack also concentric with 110 the gear wheel, and a movable stop adjustable on said segmental rack and arranged in the path of the handle to limit the throw thereof in the rearward direction and the rotation of the platen.

3. In a paper holding carriage for adding machines and the like, a platen journaled 115 in the carriage frame, a pinion rotatable therewith, a gear wheel meshing with said pinion, an operating handle journaled concentrically with said gear wheel, a pawl and ratchet connection between said handle and gear, a fixed stop limiting the throw of the handle in one direction, a rocking arm pivoted concentrically of the gear wheel and equipped with a stop for limiting the throw of the arm in the other direction, and means 120 for locking said arm in various positions of angular adjustment.

4. In a paper holding carriage for add- 130

ing machines and the like, one of the end plates of the carriage having an upward extension equipped with a fixed stop, a pivot and a segmental rack concentric with the pivot, a platen journaled in the end plates, a pinion rotating with the platen adjacent said upward extension, a gear wheel rotatable on said pivot, an operating lever mounted to rotate concentrically of said pivot and arranged to contact said fixed stop at the limit of its movement in one direction, a ratchet connection between said operating lever and gear wheel, and a movable stop adjustable on said segmental rack for limiting the movement of the operating handle in the other direction.

5. In a paper holding carriage for adding machines and the like, one of the end plates of the carriage having an upward extension equipped with a fixed stop, a pivot, and a segmental rack concentric with the pivot, a platen journaled in the end plates, a pinion rotating with the platen adjacent said upward extension, a gear wheel rotatable on said pivot, an operating lever mounted to rotate concentrically of said pivot and arranged to contact said fixed stop at the limit of its movement in one direction, a ratchet connection between said operating lever and gear wheel, an arm 24 mounted to rotate on said pivot, a pawl on said arm arranged to engage said rack at various positions of adjustment, said arm having a stop contact arranged to interfere with said operating lever to limit its movement in the reverse direction.

6. In a paper holding carriage for adding machines and the like, one of the end plates of the carriage having an upward extension equipped with a fixed stop, a pivot, and a segmental rack concentric with the pivot, a platen journaled in the end plates, a pinion rotating with the platen adjacent said upward extension, a gear wheel rotatable on said pivot, an operating lever mounted to rotate concentrically of said pivot, and arranged to contact said fixed stop at the limit of its movement in one direction, a ratchet connection between said operating lever and gear wheel, a movable stop adjustable on said segmental rack for limiting the movement of the operating handle in the other direction, a cover plate fast upon said pivot, said cover plate bearing an index scale indicating the rotation given the platen by the operating lever at the various positions of adjustment of the movable stop.

7. In a paper holding carriage for adding machines and the like, one of the end plates of the carriage having an upward extension equipped with a fixed stop, a pivot, and a segmental rack concentric with the pivot, a

platen journaled in the end plates, a pinion rotating with the platen adjacent said upward extension, a gear wheel rotatable on said pivot, an operating lever mounted to rotate concentrically of said pivot and arranged to contact said fixed stop at the limit of its movement in one direction, a ratchet connection between said operating lever and gear wheel, a movable stop adjustable on said segmental rack for limiting the movement of the operating handle in the other direction, and a sector-shaped cover plate fast upon said pivot and having a segmental flange opposite said segmental rack, said flange being provided with an index scale indicating the rotation given the platen by the operating lever at the various positions of adjustment of the movable stop.

8. In a paper holding carriage for adding machines and the like, one of the end plates of the carriage having an upward extension equipped with a fixed stop, a pivot, and a segmental rack concentric with the pivot, a platen journaled in the end plates, a pinion rotating with the platen adjacent said upward extension, a gear wheel rotatable on said pivot, an operating lever mounted to rotate concentrically of said pivot, and arranged to contact said fixed stop at the limit of its movement in one direction, a ratchet connection between said operating lever and gear wheel, a movable stop adjustable on said segmental rack for limiting the movement of the operating handle in the other direction, a cover plate fast upon said pivot, and a spring intermediate said operating lever and casing tending to press said lever toward said movable stop.

9. In combination with the platen and regular line-spacing mechanism of a recording machine, a gear and operating means therefor arranged to rotate the platen with multiplied movement, means for varying the length of stroke given by said gear to the platen, a scale for indicating the length of stroke, a paper support, and a scale on said support marked to indicate the length of stroke necessary to bring a given line on the sheet to the printing point of the machine.

10. In combination with the platen and regular line-spacing mechanism of a recording machine, a gear and operating means therefor arranged to rotate the platen of the machine with a relatively long stroke, a scale for indicating the length of stroke, a paper support, and a scale on said support marked to indicate the length of stroke necessary to bring a given line on the sheet to the printing point of the machine.
